UNITED STATES PATENT OFFICE.

JOB HUTCHINSON, OF SAUGERTIES, NEW YORK.

TRAIN INDICATOR.

Application filed July 21, 1922. Serial No. 576,589.

To all whom it may concern:

Be it known that I, JOB HUTCHINSON, a citizen of the United States, residing at Saugerties, in the county of Ulster and State of New York, have invented certain new and useful Improvements in Train Indicators, of which the following is a specification.

This invention relates to changeable exhibitors or signs, and more particularly to indicators such as are used in large railway terminals to inform the public as to the leaving time and route of the trains on the various tracks.

As is well known, such railway terminals usually comprise a concourse separated from the train shed or sheds by means of a barrier, usually in the nature of an iron fence, and gate ways are provided for admitting passengers desiring to board the trains, all passengers wishing to take any particular train being compelled to pass through the same gate way. It is also customary to arrange above such gate ways suitable signs indicating the track number, destination, and time of leaving of the various trains.

It is often desirable to provide two closely adjacent gate ways and one object of the present invention is to provide a reversible sign board or indicator which may be swung into a position over either one of such gate ways as desired.

A further object of the invention is to devise means whereby the sign board or frame carrying the sign cards may be lowered from its elevated display position, into a position where it is accessible to an attendant standing on the floor, for the purpose of changing the cards.

With the above and other objects in view, I have devised a vertical supporting column adapted to be secured to or form a part of the usual iron work of the fence, and having a sign structure mounted thereon in such manner that it may be both raised and lowered and swung in a horizontal plane, and I have also provided means whereby the sign structure, when in its operative or display position, is locked against vertical movement. The invention also comprises numerous subsidiary features and improved details of construction, all as will appear from the following description and be pointed out in the appended claims.

In order that the invention may be readily understood, reference is had to the accompanying drawings, forming part of this specification, and in which:—

Fig. 1 is a front elevation of one form of my improved sign or train indicator;

Fig. 2 is a side elevation thereof, parts being broken away, and the inoperative position of the sign being indicated in dotted lines;

Fig. 3 is a rear elevation of the sign shown in Fig. 1;

Fig. 4 is a side elevation of the sign board itself, indicating various positions of the parts, by dotted lines;

Fig. 5 is a front elevation of the sign board itself.

Fig. 5^a is a fragmentary enlarged section, substantially on the line 5^a—5^a of Fig. 5;

Fig. 6 is a plan view of the sign or indicator shown in Fig. 3;

Fig. 7 is a detailed fragmentary sectional elevation, showing my improved positioning and locking means;

Fig. 8 is a transverse section on line 8—8 of Fig. 7;

Fig. 9 is a front elevation of a slightly modified construction of indicator, as employed in connection with a fence comprising extensive iron work, parts being in section;

Fig. 10 is a rear elevation of the sign structure shown in Fig. 9.

Fig. 11 is a plan view thereof;

Fig. 12 is a vertical section substantially on the line 12—12 of Fig. 9;

Fig. 13 is a fragmentary section substantially on the line 13—13 of Fig. 9.

Figs. 14 and 15 are a fragmentary elevation and vertical section, respectively, on an enlarged scale, showing a detail of construction hereinafter described; and

Figs. 16 and 17 are an elevation and plan respectively, of the improved card holder or receptacle, used in connection with the time indicating device shown in Fig. 12.

Referring to the drawings in detail, and more particularly to Figs. 1 to 8 thereof, the reference character 1 designates a hollow iron post which may or may not form a part of the usual iron fence. At the top and at the rear of this post is an opening in which is mounted a bracket 2 secured to and uniting the upper ends of a supporting column or rod 3, outside of the post and spaced

slightly therefrom, and a second rod or guide 7^a disposed centrally inside of the post. The lower end of the rod or column 3 is set in a socket or boss 4, carried by the base of 5 the post 1.

Mounted on the column 3 and capable of both rotary and longitudinal movement thereon, is an elongated sleeve 5 which serves to carry the sign board hereinafter 10 described. In order to support this sleeve and balance the weight of the sign board structure, I provide a counterweight 6^a, arranged to slide on the guide rod or column 7^a within the post 1, and connected to the sleeve by 15 means of a chain or other flexible element 6, passing over a pulley 7, journaled in the bracket 2.

In order to prevent the chain 6 from twisting when the sleeve 5 is rotated, I preferably 20 attach the chain to the sleeve by means of a swiveled ball bearing collar 38, supported by a yoke 37, as clearly shown in detail in Figs. 14 and 15.

As clearly shown in Figs. 7 and 8, the column 3 is provided with a longitudinal groove 9, extending throughout a portion of the length thereof, and adjacent the upper 25 end of the groove 9 is a transverse or semi-annular intersecting groove 10, which latter 30 extends for approximately 180°, as clearly shown in Fig. 8. Preferably the longitudinal groove 9 is extended slightly above the transverse groove 10, as shown at 9^a in Fig. 7, so as to permit the free action of the buffer springs, hereinafter described. A pin or 35 set screw 11 carried by the sleeve 5 engages with the grooves 9 and 10, as shown in Figs. 7 and 8.

At the upper and lower ends of the rod or 40 column 3 are arranged buffer springs 12 and 13, respectively, against which the ends of sleeve 5 strike, as the sleeve reaches the upper and lower limits of its movement, such 45 springs serving to cushion the impact which would otherwise be objectionable.

Rigidly secured to the sleeve 5, as by 50 split cuffs 42, are one or more horizontal arms, two of such arms 14 being shown in the drawings. These arms are provided at 55 their outer ends with alined sleeves, through which passes a vertical rod or shaft 15, which rod is rigidly clamped into position in said arms, as by means of set screws 16.

The sign board or frame in its entirety, is 60 designated by the numeral 17, and as shown, is rectangular in shape. It is provided at its back with two centrally disposed alined bearings 18, in which are received the ends of the rod 15.

By virtue of the above described construction, it will be obvious that the sign board 65 17, as a whole, can be rotated around the shaft 15 as a center, as indicated by the dotted arrows *y* in Fig. 6, and that the sign board, with the arms 14, can be swung

around the rod 3 as center, as indicated by the curved arrow *x* in Fig. 6.

In order, however, to hold the sign board 17 in a position parallel with the face of post 1, as shown in Fig. 6, and to accurately 70 adjust it to such position, I provide a bracket 19 which may be locked to the shaft 15 by means of set screws 20 and which carries at its ends bearing studs 21, which may be screwed in or out, so as to adjust to a 75 nicety the angular position of the sign board 17, relative to the shaft 15.

Referring now to Figs. 4 and 5, the sign board 17 comprises a main outer frame in the upper part of which is arranged a panel 80 22 for indicating the track number, as shown in Fig. 1. Below this panel is arranged a sub-frame 24, pivoted at its lower edge to the main frame, as indicated at 85 26. The pivot pins 26 are carried by lugs 27, which project out beyond the plane of the sign board, and the sub-frame is provided with pivot lugs 26^a, which are also offset, as shown in Fig. 4, so that when the sub-frame 90 occupies its normal position within the main frame, it will be maintained in such position by gravity.

At the upper end of the sub-frame 24 is pivotally mounted, as at 25, the time indicating device 23. The details of this are not 95 important, but it preferably comprises a panel or card holder having four openings 23^a, as shown, adapted to receive interchangeable cards, bearing on their face, numerals serving to indicate time.

At the top of the time indicating device 100 is provided a hook 28 or the like, which may be engaged by a suitable pole, so that an attendant standing on the floor can swing the sub-frame 24 on its pivot in the arc of a circle, as indicated at *z* in Fig. 4.

The large sign card indicating the name of the railroad company and the destination of the train is designated at 29. This card usually consists of a piece of sheet 110 metal provided with a wire beading around its edges, such wire being shown at 31 in Fig. 5^a. Slots 32 are formed through the sign card 29, adjacent the wire 31, at the 115 upper edge of the card, and in my improved arrangement, these slots are adapted to be engaged over hooks 30, secured to the lower edge of the time indicating device, 23, as clearly shown in Fig. 5^a. Thus, the sign card 29 is detachably secured to and freely 120 suspended from the time indicating device 23. Therefore, when the sub-frame 24 is swung on its pivot 26, as indicated by dotted lines in Fig. 4, the time indicating device 23 and the attached sign card 29 also 125 swing out from the sub-frame by gravity, and maintain a vertical position as the sub-frame is swung downward through 180°. When the lowermost position is reached, as shown at the bottom of Fig. 4, the time 130

changing device 23 has been swung down into a position where it is low enough to be accessible to an attendant standing upon the floor, and when in this position, the 5 cards can be readily changed.

It will be readily understood from the foregoing that the arms 14 may be swung around the rod or column 3, so as to bring the sign board 17 on either side of the post 10 1, as indicated in full and dotted lines in Figs. 1, 3, and 6. This swinging movement is permitted by reason of the fact that the pin 11 travels in the transverse or semi-annular groove 10, and it will be apparent 15 that so long as the pin is in this groove, the sleeve and associated sign structure are locked against vertical movement. When, however, the arms 14 and sign board are swung half-way around between the two 20 display positions and stopped in the position shown in dotted lines in Fig. 2, so that the pin 11 is in alinement with the vertical groove 9, in the column 3, the pin can pass from the groove 10 into the groove 9 and 25 thus permit the sleeve to freely travel up and down on the supporting column. The purpose of lowering the sleeve and sign board into the dotted line position shown in Fig. 2 is, of course, to bring the sign 30 board down within reach of an attendant standing on the floor so that the cards may be changed.

When the sign board 17 is swung from full line to dotted line position, as shown in 35 Figs. 1, 3 and 6, it is, of course, necessary to reverse the board in order that the sign may always face in the same direction. This is accomplished by simply loosening the set screws 20 and swinging the sign 40 board around the shaft 15 as a center, as indicated by the arrows *y* in Fig. 6. Thus, by virtue of this double swinging movement around both the rods 3 and 15, the sign board may be moved from one side of the 45 post to the other, and yet be caused to face in the same direction. Moreover, the relation of the figures and letters constituting the sign, to the observer, is preserved, so that no confusion results in the reading of 50 the sign.

It will be noted that I have shown and described two different methods of lowering the sign board into a position where it is accessible to the attendant, one of these 55 methods being shown in Fig. 2, and the other in Fig. 4. It is desirable to combine both of these into the same structure, as shown in the drawings, so that in case one means of lowering should in any way become inoperative, the other means may be employed. Thus, continuous operation of the indicator is assured, and emergencies are provided for.

In Figs. 9 to 13, I have illustrated a 60 65 slightly modified construction of my invention

tion, adapted for use in connection with fences comprising continuous iron panels. Such fences commonly comprise a series of hollow posts, such as 1^a and 1^b, forming part of the iron work, the passenger gate 70 ways being located between posts, and below the iron panel work.

In the present modification, I employ the fundamental parts similar to those described in connection with the first modification, and similarly lettered, including the columns 3 and 7^a, the counterweight, pulley, chain, etc. The sleeve which carries the sign structure is designated 35, and its upper end is of special construction, as 75 shown in Figs. 14 and 15, it being understood that such construction is also contemplated in Figs. 2 and 3. By reference to these Figs. 14 and 15, it will be seen that around the upper end of the sleeve 80 35, which is comparatively thin, is fitted a relatively heavy cuff 35^a, held on by set screws 35^b. The chain 6 is attached directly to a lug 40, carried by a yoke consisting of a ring 37, having arms 39, pivoted at their 85 lower ends to diametrically opposite points of a swiveled ring 38, having therein another flanged ring 38^a, carrying upper and lower raceways, 38^b and 38^c, between which run balls 38^d, the upper raceway 38^b, resting against the lower edge of the cuff 35^a. A wear ring 35^e is preferably fitted in the upper end of the cuff 35^a, and is secured 90 therein by set screws 35^f. Set into the upper end of the sleeve 35 and cuff 35^a 100 is a set screw or pin 36, the inner end of which works in the grooves 9, 10. It will be noted that in this modification, this pin is placed at the upper end of the sleeve instead of at its lower end, as in Fig. 2, and 105 consequently, the grooves 9 and 10 are located in the upper part of the column or rod 3. However, a set screw 41^a may be employed at the lower end of the sleeve 35, if desired, as shown in Fig. 12, to aid in 110 clamping the sleeve in position. This set screw works through a cuff 35^e, located at the lower end of the sleeve, and carrying a wear ring 35^f, held in by screws 35^g. In 115 order to prevent twisting of the chain 6, I provide a set screw or pin 41, which extends through the ring 37 and engages in the groove 9. Thus, as the yoke and sleeve shown in Figs. 14 and 15 slide up and down the rod 3, the sleeve can freely turn 120 in the swivel ring 38 when the pin 36 reaches the transverse groove 10, but the yoke to which the chain is attached is prevented from turning by reason of the engagement of the pin 41, in that portion 125 of the groove 9 which is above the groove 10.

The supporting arms are designated at 44, and are shown as secured to the sleeve 35 by means of split cuffs 42, united by bolts 43. The arms 44 are secured to the 130

5 shaft 15 by set screws 46, and the sign board, which is designated 47, is provided with alined bearings 48 which are journaled on the shaft 15. The sign board, as shown in Figs. 9, 10 and 13, is of slightly different construction from that previously described, being lightened by having portions cut away from the interior thereof, as indicated at 49. Adjacent its four corners the sign 10 board is preferably provided with projecting lugs 47^a, carrying bumpers 47^b formed of rubber or the like, which are adapted to engage the rear of posts 1^a and 1^b to limit the forward movement of the sign board and 15 prevent noisy contact.

50 designates the iron work panel at the rear of the translucent panel 52 carrying the track number as shown in Fig. 9, lamps 51 being preferably disposed between the panels 50 and 52, to illuminate the latter.

Below the panel 52 is an opening 55 in the iron work panel 56, such opening being made to expose the face of the time indicating device designated at 53. This time indicating device differs slightly from the one previously described, in that it is offset from the main sign board 47 and lies in a plane in front thereof. The time indicating device 53 is carried at the forward end of truss arms 53^a, secured at their rear to upstanding brackets 54, carried by the sign board 47.

Just below the opening 55, the iron work recedes and an opening 61 is provided between the posts 1^a and 1^b of such size and shape as to exactly register with the sign board 47. 62 designates a cross beam or molding of the iron work, extending between the posts below the sign.

40 The sign card shown in connection with the sign board illustrated in Fig. 13 comprises a piece of sheet metal 59 which is removably held on the sign board by means of two pairs of brackets 58 and 58^a. The
45 sign card is made narrower than the distance between the bodies of these brackets and the ends of the brackets are bent to form flanges which serve to retain the sign card in position, the upper flange being longer than the
50 distance between the upper edge of the card and the body of the upper brackets. Thus, when it is desired to remove the card 59, it is simply lifted until its lower edge clears the flanges of the brackets 58, when such
55 lower edge may be swung outwardly, as indicated in dotted lines in Fig. 13, and the card removed.

The panel 56 of the iron work which is just below the time indicating device is preferably extended downwardly to form a canopy 57, and behind this canopy may be arranged one or more electric lamps 60, so disposed as to illuminate the face of the sign card 59.

65 63 designates the usual sliding door for

controlling the gate way. In its open position, this door slides back directly under the sign board 47.

Preferably mounted between the brackets 54 at the top of the sign board 47, is a storage box or receptacle 64 for containing the interchangeable cards used in the time indicating device. This box or receptacle is shown in elevation and plan in Figs. 16 and 17. The box is preferably formed of end pieces with slanting upper edges 65 and is provided with intersecting partitions 66, dividing the interior of the box into a number of compartments, each adapted to contain cards bearing the same indicia. Owing to the fact that the cards bearing the digits 6 and 9 are similar, but reversible, I have found that a box with eight compartments, as shown, suffices to contain all of the necessary cards.

The method of operating the sign shown in Figs. 9 to 13, is substantially the same as that heretofore described, except that in the latter modification, the sign is not shown as reversible. In this case, however, the same advantages are present in regard to lowering the sign board in order to bring it into an accessible position. When it is desired to do this, the sign structure, together with the sleeve 35, is swung around on the column 3, until the pin 36 registers with the groove 9, and then the sleeve and sign structure may be moved down along the column 3, until the sign can be readily reached by an attendant. 100

It will be noted that in both modifications, substantially the same principles are employed, and it will be understood that the method of holding the sign card, shown in Fig. 13, may be equally well used, in connection with a reversible sign, such as shown in Figs. 1 and 3, instead of the swinging sub-frame arrangement therein illustrated. 105

It will also be understood that the counter-weight 6^a is preferably made equal to the weight of the sleeve and sign structure, so that such structure will remain stationary in whatever position it may be caused to occupy. 110

What I claim is:—

1. A reversible sign comprising a support, an arm pivotally mounted at one end on said support, to swing in a horizontal plane, a sign board carried at the other end of said arm and pivoted so as to swing in a horizontal plane relative thereto, and means for holding said sign board in any one of a number of vertical planes making different angles with said arms. 120

2. The combination with a vertical column, supported at both ends, of a sign-board, means for supporting said sign-board on said column at the side thereof so that it is capable of swinging about the same, said supporting means and sign-board

- being also capable of longitudinal movement on the column when in one predetermined angular position, and interengaging parts carried by said supporting means and 5 columns for automatically locking said supporting means and sign-board against longitudinal movement when swung to any other angular position on either side of the first mentioned position.
- 10 3. The combination with a vertical supporting column, of means for pivotally supporting a sign thereon to gyrate around the same into operative or display and inoperative or idle positions, said sign, when swung 15 into inoperative position, being capable of moving longitudinally of said column, whereby said sign may be raised and lowered, and said column and supporting means having parts brought into engagement by the swinging of the sign into operative or display position for locking it 20 against longitudinal movement.
4. The combination with a vertical supporting column, of a sleeve both slidable 25 and rotatable on said column, a sign carried by said sleeve laterally thereof, said column and sleeve having interengaging parts whereby the sleeve is locked against sliding movement except when in a single predetermined angular position.
5. The combination with a vertical supporting column, of a sleeve mounted for both rotary and sliding movement thereon, a sign carried by said sleeve, said column 35 having intersecting longitudinal and transverse grooves, and said sleeve having a pin working in said grooves, whereby, when said sleeve slides on the column, said pin travels in said longitudinal groove, and 40 when said sleeve is rotated so as to cause said pin to enter said transverse groove, the sleeve is locked against sliding movement.
6. The combination with a vertical supporting column, of a sleeve both slidable on 45 said column and rotatable therearound, a sign carried by said sleeve, and a counterweight for balancing the weight of said sleeve and sign, whereby they will remain in any vertical position to which they are 50 adjusted.
7. The combination with a hollow post, of a fixed supporting column carried thereby in spaced parallel relation, a sign mounted on said column for vertical movement 55 along the same, a pulley mounted at the top of said post and a flexible element passing over said pulley, said element being attached at one end to said sign, and a counterweight attached to the other end of 60 said element, and movable inside of said hollow post.
8. The combination with a pair of mechanically and rigidly connected parallel spaced columns, of a sign vertically movable along one column, a counterweight ver- 65
- tically movable along the other column, a pulley mounted at the upper end of said connected columns, and a flexible connection extending over said pulley and attached at its ends to said sign and said counterweight respectively. 70
9. The combination with a supporting column of a sleeve mounted for both rotary and sliding movement on said column, a sign board carried by said sleeve, a counterweight for the sign board and sleeve, a 75 chain connecting the counterweight and sleeve, and means for attaching one end of the chain to the sleeve, said means including a swiveled member whereby said sleeve may freely rotate without twisting the chain. 80
10. The combination with a vertical column, of a sleeve movable both angularly and longitudinally thereof, a sign board carried by said sleeve, a chain for supporting the weight of said sign board and sleeve, and means for connecting said chain to the sleeve, said means comprising a swiveled member, and a yoke connected with said 85 swivel member and having means to which the chain may be secured, and means for positively locking said yoke against rotation while permitting the sleeve to freely revolve. 90
11. The combination with a sign board comprising a frame, and means for supporting it at such a height as to be normally inaccessible, of a sub-frame, pivotally mounted at its lower edge in said frame, and capable of swinging through 180° on its pivots, and a changeable sign pivotally carried by said sub-frame, and always facing in the same direction, whereby when said 100 sub-frame is swung downwardly on its pivots, said changeable sign is brought within the reach of an operator. 105
12. The combination with a sign board and means for normally supporting the same in a position so elevated as to be inaccessible from the floor, of a frame pivotally mounted at its lower edge on said sign board, and capable of swinging downwardly through 180°, and a changeable sign pivotally carried by said frame, and always 110 facing in the same direction, whereby when said frame is swung downwardly about its pivots, such sign is brought within reach of an operator standing on the floor. 115
13. The combination with a train indicator, comprising a main frame, of a sub-frame pivotally mounted on said main frame, a time indicating device pivotally mounted at its upper edge in said sub-frame, and a sign card detachably secured to the lower edge of said time indicating device. 120
14. In a train indicator, the combination with the main frame, of a sub-frame pivotally mounted thereon, and normally oc- 125 130

cupying a vertical position, a time indicating device pivotally supported at the top of said sub-frame, and a sign card suspended from the lower edge of said time indicating device, and normally lying within said sub-frame.

15. The combination with an iron-work fence having an opening, and a supporting column at one side of the fence, of a sleeve 10 both rotatably and slidably mounted on said column, an arm rigid with said sleeve, and a sign board carried at the end of said arm, whereby said sign board may swing horizontally around said supporting column 15 into position to register with and substantially fill said opening, and out of such

position, and whereby, when thus swung out of position, the sign board may be raised and lowered at will.

16. The combination with a hollow post, 20 of a supporting column mounted adjacent thereto, a sign board slidably mounted on said supporting column, a guide rod within said hollow post and rigidly connected at its upper end with said supporting column, and a counterweight mounted to travel on said guide rod within said post and connected with said sign board.

In testimony whereof I affix my signature.

JOB HUTCHINSON.
